UNITED STATES PATENT OFFICE.

RICHARD LOSSING, OF SOUTH PASADENA, CALIFORNIA.

LIQUID REGISTER.

Application filed April 11, 1921. Serial No. 460,427.

To all whom it may concern:

Be it known that I, RICHARD LOSSING, a subject of the King of Great Britain, residing at South Pasadena, in the county of Los Angeles and State of California, have invented new and useful Improvements in Liquid Registers, of which the following is a specification.

This invention is a liquid register for the fuel consumption of an internal combustion engine and consists in the provision of a register which may be of the type shown in my co-pending application Serial No. 426,828, filed November 27, 1920, and an actuating means for said register including an operating diaphragm which is normally expanded and which is adapted to be contracted by succeeding pulsations through a usual vacuum feed system, such as is employed for the fuel supply to an internal combustion engine.

The invention will be readily understood from the following description of the accompanying drawings, in which:

Figure 1 is a side elevation partly in vertical section of a meter connected to a usual vacuum feed tank by the improved operating connection.

Fig. 2 is a transverse section on the line 2—2 of Fig. 1.

In the drawings I have shown a usual vacuum feed tank at 1 which is provided with a usual connection 2 leading to a fuel supply, and with a connection 3 leading to the manifold of the engine in usual manner, so that the suction through the intake manifold will create a vacuum in the feed tank, said vacuum being employed to create pulsating suctions in the feed tank for drawing supplies of fuel to said feed tank in proportion to said pulsating suctions. From the feed tank, the fuel is supplied to a usual carburetor.

The device, as thus described, is of standard construction, and the operation thereof will be readily understood by those skilled in the art, it being understood that variations in the amount of fuel supplied to the vacuum tank, and from thence to the carburetor, will cause corresponding variations in the suction pulsations in said tank.

The vacuum feed tank is provided with a usual nipple 5 normally closed by a plug, and the improved operating connection for the fuel registering apparatus is connected to the vacuum feed tank by removing the

plug from nipple 5 and connecting a conduit 6 to the opening formed by said nipple, as by a usual nut 7.

As previously stated, the register which is employed may be similar to that shown and described in my above mentioned co-pending application, said register including a casing 8 having the registering mechanism 9 actuated by the longitudinally movable transverse plate 10. The pulsations through the vacuum feed tank will cause corresponding suctions in conduit 6 opening to said feed tank, and this conduit is connected to an operating mechanism arranged within the end of casing 8 to cause corresponding movements of said operating mechanism. The operating mechanism is in turn connected to transverse plate 10 so that the register is actuated in accordance with the pulsations through the vacuum feed tank, and as a consequence the register will register the fuel consumption, it being understood that the register is graduated for proper readings in accordance with the amount of fuel drawn into the vacuum feed tank, and which is in turn proportional to the suction pulsations in said feed tank.

The operating mechanism for the transverse plate 10 includes an annular receptacle 12 having a flexible diaphragm 13 over its open end which is turned toward transverse plate 10. The flexible diaphragm is held in position by a retaining ring 14 threaded onto receptacle 12. The device, as thus described, is mounted within the open end of casing 8 with a ring 15 threaded onto receptacle 12 abutting against the end of casing 8, and a retaining cover plate 16 received over the device and threaded onto the end of casing 8.

The diaphragm 13 is normally held in expanded position by means of coil spring 17 within receptacle 12, and impinging at its respective ends against the diaphragm and against the base of the receptacle. The base of receptacle 12 and cover plate 16 are provided with axial openings receiving a nipple 18 opening into receptacle 12, and the protruding end of this nipple is connected to conduit 6 as by a usual nut 19. By this arrangement it will be seen that the suction pulsations through conduit 6 will cause corresponding suctions in receptacle 12 so as to contract diaphragm 13 against the tendency of spring 17, and that as soon as the suction ceases, the diaphragm will be returned

to its expanded position under the influence of its spring. As a consequence the diaphragm of the operating mechanism will be moved back and forth in accordance with the pulsations through the vacuum feed tank, which are proportional to the fuel supply to the feed tank and the consequent discharge of said fuel to the carburetor, as previously described.

10 This arrangement will cause variations in the fuel consumption and the consequent variations in the frequency of the suction pulsations through the vacuum feed tank to cause corresponding variations in the movement of diaphragm 13, and the latter being connected to the transverse plate 10, the register mechanism will be variably actuated in accordance with the variations in the fuel consumption so as to accurately register the fuel being used.

The operating connection between diaphragm 13 and transverse plate 10 is preferably a universal joint connection in order to permit of relative movements of the parts, and for this purpose the adjacent surfaces of plate 10 and of diaphragm 13 are provided with co-operating bearing recesses 22, each adapted to receive a head 23 upon a connecting rod 24. It will thus be noted that the contractions of diaphragm 13 will pull transverse plate 10 so as to cause successive movements of the registering mechanism.

The construction, as thus set forth, provides extremely simple but accurate means for operating a register through the pulsations in a usual vacuum feed tank for the fuel supply to an internal combustion engine so as to register the fuel consumption.

While in the present embodiment of the invention I have illustrated a register and an

operating connection for the same employed for measuring the fuel consumption of an internal combustion engine, it will be apparent that the invention contemplates the provision of any register mechanism adapted 45 to be actuated by an operating connection moving in response to fluid pulsations.

Various changes may be made without departing from the spirit of the invention as claimed.

What is claimed—

1. In a vacuum feed device, a casing, a register including a plate mounted for movement, a diaphragm within the casing and having operative connection with said plate, a spring for urging the diaphragm in the direction of the plate, and a conduit establishing communication between said tank and the spring side of said diaphragm whereby the suction pulsations occurring in the tank 60 will operate to move said diaphragm against the action of said spring to actuate said plate.

2. In a vacuum feed device, a casing, registering means within the casing and including a movable plate, a receptacle within the casing, a retaining ring mounted on the receptacle, a diaphragm secured between the ring and receptacle, a universal connection between said diaphragm and plate, a spring 70 interposed between the diaphragm and receptacle for urging the former in the direction of the plate, and a conduit establishing communication between the tank and the spring side of said diaphragm for the purpose described.

In testimony whereof I have signed my name to this specification:

RICHARD LOSSING.
